UNITED STATES PATENT OFFICE.

CARL EUGENE SIMS, OF ABILENE, TEXAS.

DOUCHE.

Application filed July 24, 1920. Serial No. 398,642.

To all whom it may concern:

Be it known that I, CARL EUGENE SIMS, a citizen of the United States, and a resident of Abilene, in the county of Taylor and State of Texas, have invented certain new and useful Improvements in Douches, of which the following is a specification.

My invention is an improvement in douches, and has for its object to provide 10 a douche especially adapted for the prevention and home treatment of women's diseases, wherein a pipe or nozzle is provided, adapted to be interposed into the cavity to be treated, and having a base for closing 15 said cavity, and having in connection therewith a speculum for spreading the walls of the cavity to insure the thorough application of the medical preparation.

In the drawings:

20 Figure 1 is a front elevation of the improved douche,
Figure 2 is a longitudinal section,
Figure 3 is a section on the line 3—3 of Figure 2,
25 Figure 4 is an end view.

In the present embodiment of the invention, there is provided a pipe or nozzle 1 of suitable cross section, and having in connection therewith a relatively large base 30 2 which as shown, is flanged at its margin as at 3 to strengthen the same and reinforce the edge. That end of the pipe adjacent to the base is closed by the base, and that end remote from the base has a door or valve 35 4 connected therewith, which is adapted to be opened in a manner to be presently described when desired.

40 A plunger or piston 5 is arranged within the pipe, and a rod 6 is connected with the plunger, the rod extending through the base as shown, and having a finger-piece 7 for convenience in manipulating the same. A coil spring 8 encircles the rod between the plunger and the base, and normally acts to 45 press the plunger toward the gate or valve 4.

Douche pipes 9 are arranged outside the pipe 1, the said douche pipes being six in number in the present instance, and they are perforated at intervals as clearly shown in 50 Figure 1. At their outer ends, these pipes or tubes are supported by a ring 10, and at their inner end they connect with a hollow ring 11 which encircles the inner end of the pipe.

55 An intake tube 12 extends from the pipe 11 through the base, and may be connected

with a suitable source of supply for a medicinal fluid. A hood 13 of rounded form, is arranged on the inner face of the base, the said hood encircling the pipe 1 and the 60 douche tubes 9, and this hood is adapted to receive the outflow from the cavity being irrigated, and the fluid escapes from the said hood by means of a pipe 14 which extends through the base. 65

A series of speculum blades 15 is connected with a ring 16 which is supported by the douche tubes near the ring 11, and within the hood, each blade being hinged to the ring. A second ring 17 is mounted to slide 70 on the pipe 1, and this ring is connected by spreaders 18 with the speculum blades.

Links or rods 19 are connected with the ring 17, and extend through openings in the base, and the rods are bent inwardly toward 75 each other and connected outside the base. Referring to Figure 1, it will be seen that the connection between these rods, of which there are two, is laterally offset, and is provided with a finger piece indicated at 20, 80 for convenience in operating the spreader ring.

Referring to Figures 1 and 2, it will be seen the the spreader blades are pointed and curve inwardly from the outer end of the 85 pipe 1 when they are closed. They close with the douche tubes between the adjacent edges of the blade, as clearly shown in Figure 4. Means is provided for holding the speculum blades in open position. The said 90 means consists of a series of ratchet teeth 21 on one of the rods 19, and these teeth are adapted to engage the edge of the opening in the base through which the rod slides. 95

The plunger rod 6 has a lug 22 for limiting its inward movement with respect to the pipe 1, and the gate or valve 4 is opened by means of a crank 23. This crank passes through an opening in the base and is connected to the gate or valve, which is pivoted 100 to the pipe 1, and the crank shaft has a crank 24 by which it may be turned to swing the gate open.

The improved douche is used as follows: 105. With the parts in the position of Figure 1, the douche is introduced into the cavity to be irrigated or treated, and a source of supply for a medicated liquid is connected to the pipe 12 while the pipe 14 is connected with a waste. After the pipe has been introduced, and the base is in contact with the patient's body, the finger piece 20 is pushed 110

upward, and this movement tends to straighten the stretchers 18 and to move the speculum blades outwardly.

This outward movement of the blades puts 5 the walls of the cavity on the stretch, exposing every part thereof to the action of the medicated liquid which is now permitted to flow through the douche pipes. The waste liquid passes out through the hood 13 10 to the waste.

When it is desired to apply dry powdered medicaments, the powder is placed in the space above the plunger, and the gate 4 is closed. The gate is opened to permit the insertion of the powder. If desired, the powder may be placed in the pipe 1 when the douche is introduced. After the cavity has been thoroughly irrigated, the supply of liquid is cut off, the gate or valve 4 is opened, 20 and the powder is ejected, thus thoroughly powdering the walls of the cavity.

I claim:

1. A device of the character specified, comprising a pipe, a series of perforate 25 douche tubes supported outside the pipe, a base connected with the pipe and having a hood encircling the pipe, a supply ring for the douche tubes within the hood and to which the douche tubes are connected, said ring having an inlet, and the hood having an outlet, a gate or valve for closing the inner end of the pipe, means for opening said gate or valve, and a powder ejecting plunger 30 in the pipe, a series of spreader blades 35 mounted about the pipe and hinged to swing toward and from the pipe, and means for simultaneously swinging said blades toward and from the pipe.

2. A device of the character specified, comprising a pipe, a series of perforate douche 40 tubes supported outside the pipe, a base connected with the pipe and having a hood encircling the pipe, a supply ring for the douche tubes within the hood and to which

the douche tubes are connected, said ring 45 having an inlet, and the hood having an outlet, and a speculum in connection with the douche, said speculum consisting of blades hinged to the douche and enclosing the same, and means for opening said blades outwardly. 50

3. A device of the character described including a series of douche tubes having perforations along their outer sides, a ring arranged on said tubes, and a speculum having blades arranged intermediate said tubes and pivotally connected to said ring to be carried thereby, and means for spreading the blades of the speculum. 55

4. A device of the character described including a series of douche tubes having perforations along their outer sides, a ring arranged on said tubes, and a speculum having blades arranged intermediate said tubes and pivotally connected to said ring to be 60 carried thereby.

5. A device of the character described comprising a pipe, a series of douche tubes supported on said pipe and having perforations along their outer sides, a hollow supply 70 ring arranged on said pipe and connected with said douche tubes, a ring on said tubes arranged adjacent said supply ring, a speculum having a plurality of blades pivotally connected to said last-mentioned ring to be 75 carried thereby, and means for spreading the blades of the speculum including a sliding ring on said pipe and spreader arms connecting said ring and said blades.

6. A device of the character specified comprising a pipe, a series of douche tubes supported outside the pipe and having perforations on their outer side, a hollow supply ring encircling said pipe and connected with said douche tubes and a plunger movable 85 longitudinally of the pipe.

CARL EUGENE SIMS.
